UNITED STATES PATENT OFFICE

136,667

DESIGN FOR A HOOK

James Lavern Gould, Mayfield, Wash.

Application September 16, 1943, Serial No. 111,136

Term of patent 14 years

To all whom it may concern:

Be it known that I, James Lavern Gould, a citizen of the United States, residing at Mayfield, in the county of Lewis and State of Washington, have invented a new, original, and ornamental Design for a Hook, of which the following is a specification, reference being had to the accompanying drawing, forming part thereof.

I claim:

The ornamental design for a hook, as shown.

JAMES LAVERN GOULD.
